UNITED STATES PATENT OFFICE

LOUIS FRANCIS, OF MIAMI, FLORIDA

SALVAGE UNIT

Application filed October 31, 1929. Serial No. 403,833.

This invention relates to a salvage unit designed primarily for reclaiming and salvaging wrecked vessels, but it is to be understood that a salvage unit constructed in accordance with this invention may be used or employed in any connection for which it is found applicable, and the invention has for its object to provide, in a manner as hereinafter set forth, a salvage unit so constructed and arranged whereby on the supply of fluid pressure thereto the unit will be controlled by pneumatic pressure to function, seize or lift the object or load to be salvaged from the bottom of the sea or from the deck of a sunken vessel.

The invention further aims to provide, in a manner as hereinafter set forth, a salvage unit so constructed and arranged for effectually raising sunken ships or the cargoes thereof, as well as for scientific purposes on sea bottoms of great depth and further for commercial or any other purposes for which it is capable of being employed.

A further object of the invention is to provide, in a manner as hereinafter set forth, a salvage unit adapted to function in water of any desired depth, especially water too deep for ordinary submarine operations by divers, and with the unit so constructed and arranged to be free from the danger of capsizing and further capable of being readily adjusted for rough weather.

A further object of the invention is to provide, in a manner as hereinafter set forth, a salvage unit which is automatic in its operation under the water, working in any depth or character of water, and especially water too deep to be practical for submarine divers, and to further provide a salvage unit which will function in any kind of sea, without the necessity of any submarine divers or other auxiliary aid going beneath the water with it to provide for the unit to perform the salvaging function.

A further object of the invention is to provide, in a manner as hereinafter set forth, a salvage unit automatically functioning, by pneumatic pressure to seize the object or cargo to be raised and further so constructed and arranged to eliminate the necessity of positioning a cable or other device under-

neath the bottom of the sunken object or cargo to be raised in order to bring it to the surface for salvage.

A further object of the invention is to provide, in a manner as hereinafter set forth, a salvage unit constructed and arranged to provide for automatically releasing a salvage load at any stage of the operation performed by the unit.

Further objects of the invention are to provide, in a manner as hereinafter set forth, a salvage unit for the purpose referred to which is simple in its construction and arrangement, strong, durable, compact, capable of being made buoyant when desired, compact, thoroughly efficient in its use, including pneumatically operated grabbing or seizing elements for the object or load to be salvaged, readily assembled, comparatively inexpensive to manufacture and operated and maintained at comparatively low cost.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a top plan view of a salvage unit in accordance with this invention.

Figure 2 is an end view thereof illustrating the grabbing or seizing elements in full lines in non-active position and in dotted lines in active position.

Figure 3 is a section on line 3-3, Figure 1.

Figure 4 is a cross sectional view of the controlling elements illustrating in full lines the normal position thereof and in dotted lines the shifted position thereof.

Figure 5 is a longitudinal sectional view of one of the elevating elements.

Figure 6 is a cross sectional view of one of the seizing or grabbing elements.

Figure 7 is a side elevation, partly broken away of a modified form of lifting element.

The unit includes a controlling element, a plurality of lifting elements, preferably 5 two, and two pairs of grabbing or seizing elements. The controlling and lifting elements are of tank-like form and can be of any desirable contour, but preferably will be of the form shown in Figures 1 to 5 of the 10 drawings. The controlling and lifting elements are arranged in parallelism and with the controlling element positioned between the lifting elements.

As shown in Figures 1 and 2, the controlling element, indicated generally at 10, gradually increases in diameter from its center towards each end and includes a pair of oppositely disposed sections 11, 12 of frusto-conoidal contour. The smaller ends of said 15 sections are flanged as indicated at 13 and oppose each other. Arranged between and common to the smaller or inner ends of the sections 11, 12 is a closure plate or bulkhead 14 which is flush with the outer edges of and secured to the flanges 13 by any suitable means. The plate 14 is formed with an eccentrically disposed opening 15 for the passage of a rod, bar or shaft 16 upon which element 10 is eccentrically mounted. The 20 element 10 moves with the rod, bar or shaft 16. The plate 14 is furthermore provided with an eccentrically disposed opening 17 for establishing communication between the chambers 18, 19 provided by the sections 11, 25 12 respectively. The outer ends of the sections 11, 12 are flanged as indicated at 20, 21 respectively. The outer ends of the sections 11, 12 are closed by head members 22, 23 respectively. The former is provided 30 with superposed, spaced vent openings 24 and the latter with superposed, spaced vent openings 25 for the compartments 18, 19 respectively. The sections 11, 12 in proximity to the flanges 20, 21 respectively, are provided with openings 26, 27 respectively, in which are secured lines 28, 29 respectively, for supplying and exhausting fluid pressure to and from and for exhausting water from the controlling element 10. The sections 11, 35 12 are provided with vent openings 11', 12' respectively. The fluid pressure employed preferably is compressed air.

Secured to the peripheries of the sections 11, 12 are spaced, circumferentially extending, reinforcing ribs 30, 31 respectively. Secured to the sections 11, 12 and extending from nipple 28 to nipple 29 is a radially disposed fin 32 having its outer edge positioned in alignment with the edges of the flanges 20, 40 21. The fin 32 is of triangular contour.

Connected to the outer faces of the head members 22, 23, eccentrically thereof are hollow, quadrant-shaped members 33, 34 respectively, having their inner sides closed by the 45 head members 22, 23 respectively and form-

ing in connection therewith chambers 35, 36 respectively which communicate with the chambers 18, 19 respectively by the openings 24, 25 respectively.

The rod 16 is suitably connected to the sections 11, 12 and also connected with the members 33, 34. The rod 16 has secured to the ends thereof the links 37, 38, the former being secured to the member 33, by the holdfast means 39, and the latter being secured to the member 34 by the holdfast means 40. Holdfast means indicated at 41, 42 are employed to rigidly secure the links 37, 38 to the ends of the rod 16. Projecting from the members 33, 34 are shouldered pins 43, 44 respectively which extend through the links 37, 38 and carry the holdfast means 39, 40.

As each of the elevating elements is of the same construction, but one will be described, as the description of one will apply to the other. One of the elevating elements is generally indicated at 45 and the other at 46. Each elevating element gradually decreases in diameter from its center towards each end and is formed from a pair of oppositely disposed, frusto-conical sections 47, 48 having the larger ends thereof abutting. The larger or inner end of the section 47 is provided with a flange 49 and such end of the section 48 is also formed with a flange 50. The flanges 49, 50 abut and are suitably secured together. The elements 45, 46 are provided with vent openings 45', 46' respectively.

The outer or smaller end of section 47 is closed by a head member 51 and the outer or smaller end of the section 48 is closed by a head member 52. Positioned at the longitudinal axis of the section 45 and extending from each end thereof is a supporting bar 53. Positioned at the longitudinal axis of the element 46 and projecting from each end thereof is a supporting bar 54. The bar 53 is of greater length than the bar 54. The section 45, as well as the section 46 is formed with spaced, circumferentially extending, 60 reinforcing ribs 55. Opening into the element 45 is a line connection 56 for supplying and pumping water to and from element 45 and also for supplying and exhausting fluid pressure to and from element 45.

Connected to and opening into element 46 is a line connection 57 for supplying and pumping water to and from element 46, as well as for supplying and exhausting fluid pressure to and from element 46.

Two pairs of grabbing or seizing elements are employed to grasp, hold and lift the object to be salvaged. The elements of each pair are oppositely disposed with respect to each other. The grabbing elements of one pair are indicated at 58, 59 and the grabbing elements of the other pair at 60, 61. Each of the grabbing elements is of hook-shaped contour and as the grabbing elements are of like construction, but one will be described, as the 125 130

description of one will apply to the other. Each grabbing element comprises a shank 62 terminating in a hook 63. Each grabbing element includes a series of parallel, spaced 5 sections 64, 65, 66 and 67 of equal length. See Figure 7. Positioned against the top of the said sections, as well as being secured therewith is a top member 68. Positioned against the bottom of and secured to said sections is a bottom member 69. The members 10 68, 69 overlap sections 64, 67. The sections 64, 65, 66 and 67 in connection with the members 68, 69 provide compartments 70, 71 and 72 extending lengthwise of the elements. The 15 sections 65 and 66 are provided with openings 73, 74 for establishing communication between the compartments. Each top member 68 is formed with a combined exhaust and intake 68', near its upper terminus.

20 The section 67 is formed with a water intake 75 and a plurality of spaced, normally closed check valves 76 for the discharge of air from the compartments on the intake of water to the elements. The water received in said 25 elements increases the weight of the latter. At the water enters the air within the compartments will be forced through the check valves 76, under such conditions permitting of a larger amount of water entering the 30 grabbing elements than would be the case if an air cushion were formed therein. The shanks 62 of the grabbing elements are pivotally mounted on the rod 16 and positioned below the compartments 35, 36.

35 Connected to and extending from the shanks 62 of the elements 59, 61 are links 77 which are pivotally mounted on the other end of the bar 53. A pair of bolts 78, 79 provided with nuts 80 are employed for connecting the links 77 to the shanks 62 of the grabbing elements 59, 61. The shanks 62 of the grabbing elements 58 and 60 are connected to the ends of the bar 54 by links 81. The links 81 are pivotally mounted on the bar 54. The shanks 62 of the grabbing elements 58 and 60 are connected to the links 81 by a pair of bolts 82, 83 carrying nuts 84. When the unit is at the level of the water, the bolts 79 and 82 may be removed and under those conditions 40 the shanks 62 can pivot on the bolts 80, 83. When the bolts 79, 82 are not removed no pivoting action can be had by the grabbing elements other than such action being imparted to the elements by the links 77 and 81 pivoting on the bars 53, 54. The last mentioned pivoting action will be had when the lifting elements move upwardly with respect to the controlling element and this will be 45 hereinafter more fully referred to.

50 Secured to the shanks 62 of the elements 59, 61, at the free ends of such shanks are tow line receiving hooks 85. Secured to the free ends of the shanks 62 of grabbing elements 58, 60 are tow line receiving hooks 86. The

hooks 85 extend in an opposite direction with respect to the hooks 86.

The grabbing elements 58, 60 are arranged in parallelism and the grabbing elements 59, 61 are arranged in parallelism. The grabbing elements 58, 60 extend in opposite directions with respect to the grabbing elements 59, 61. The grabbing elements 58, 60 are arranged inwardly with respect to the grabbing elements 59, 61.

75 The controlling element which is in the form of a tank and the lifting elements which are in the form of tanks can be of any desired length and diameter. The length of each of the grabbing elements can be as desired. The 80 hooks 63 of the grabbing elements are of arcuate contour and are tapered to provide a pointed end.

85 The controlling element functions as a retaining or anchoring means for the unit to permit of the elevating elements moving upwardly with respect to the controlling element for the purpose of shifting the grabbing elements on their pivots in a direction for the grabbing elements to grab or seize the object 90 to be salvaged. The weight of the grabbing elements with respect to the controlling element further acts to maintain the grabbing elements in engaging position with the object 95 to be salvaged.

100 In operation, assuming that a sunken boat or cargo to be salvaged has been located, the unit is towed to the place of operation and all tanks partly filled with water to cause partial submersion as an aid to towing; the unit 105 is towed directly over the point of salvage, and all tanks are filled with water. This causes the unit to accurately submerge with the grabbing elements in an open extended position, the tanks submerging with air lines and water lines attached to be operated from an independent surface boat or salvage unit equipped with the necessary pumps; the unit 110 having reached bottom or coming to rest on the sunken cargo, the controlling element is left filled with water, but the elevating elements on each side are pumped clear of water and filled with fluid pressure. This causes the elevating elements to rise towards the 115 surface, but the controlling element being filled with water has a tendency to remain stationary. The elevating elements rise with the ends of the grabbing elements attached to their axes, the grabbing elements being 120 also pivotally connected with the controlling element, and as the latter is filled with water it will have a tendency to remain stationary. The upward movement of the elevating elements causes the grabbing elements to close by automatic pneumatic pressure, thus either 125 completely enclosing the sunken cargo by the grabbing elements meeting under the bottom of the same, or causing the grabbing elements to attach themselves to the sides of the sunken cargo or ship with sufficient squeezing 130

pressure to lift the cargo or ship from the sea bottom.

As the elevating elements are completely emptied of water and filled with fluid pressure, the unit, together with the salvage load is brought to the top of the water and sufficiently close to the surface of the water to permit the easy cradling of the load on other cradle tanks placed under it or by the use

10 of cables or other devices. Once the load has been seized and having started to the surface the controlling element may be partially emptied of water and filled with fluid pressure to assist the elevating elements in coming

15 to the surface with the load. The salvage load having been properly cradled, the elevating elements are again emptied of fluid pressure and filled with water, which causes the grabbing elements to automatically dis-
tend, thus releasing the load, then the controlling element is filled with fluid pressure, compressed air which causes the unit to raise to the surface with the grabbing elements ex-
tended and free of the salvaged load and the

20 operation is complete.

When the unit is at the top of the water or near the surface thereof, the bolts 79, 82 can be removed and which will permit of the elevating and lowering of the elevating elements without imparting a pivoted move-
ment to the grabbing elements.

30 The compartments 35, 36 permit of an increased supply of water being had to the controlling element to increase the weight of the latter.

35 The fin 32 acts as a stabilizing means for the controlling element on the lowering of the unit and also as a retarding means for the controlling element when the unit rises, as the controlling element when shifted in either direction will position one of the sides of the fin 32 at an angle to the vertical to retard the rise of the controlling element whereby the latter will be held below the elevating ele-
ments to maintain the grabbing elements in lifting relation with respect to the object salvaged.

40 A modified form of lifting element is shown in Figure 6 and is generally indicated at 87. The element 87 is of uniform diameter and tank-like form, and provided with vent openings 87'.

45 Preferably the reinforcing ribs on the controlling element 10 and on the lifting elements 45, 46 will be of triangular cross section.

50 Although one embodiment of a salvage unit, in accordance with this invention is illustrated and described, it is to be understood however that changes in the constructive arrangement can be had which will fall within the scope of the invention as claimed.

55 What I claim is:

1. A salvaging unit of the submersible type comprising a controllable element adapted to

receive a weighting means therefor, a plurality of fluid pressure receiving elevating elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said grabbing elements being oppositely disposed, of hook-like form and hollow, said grabbing elements having an intake for the entrance of water thereto and valve controlled means for the discharge of air therefrom on the intake of water thereto.

2. A salvaging unit of the submersible type comprising a controllable element adapted to receive a weighting means therefor, a plurality of fluid pressure receiving elevating elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling and elevating elements having means for supplying thereto and exhausting therefrom a weighted means therefor and for supplying fluid pressure thereto and exhausting it therefrom, said grabbing elements being oppositely disposed, of hook-like form and hollow, said grabbing elements having an intake for the entrance of water thereto and valve controlled means for the discharge of air therefrom on the intake of water thereto.

3. A salvaging unit of the submersible type comprising a controllable element adapted to receive a weighting means therefor, a plurality of fluid pressure receiving elevating elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling element provided exteriorly thereof with a lengthwise extending equalizing fin.

4. A salvaging unit of the submersible type comprising a controllable element adapted to receive a weighting means therefor, a plurality of fluid pressure receiving elevating

elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling and elevating elements having means for supplying thereto and exhausting therefrom a weighted means therefor and for supplying fluid pressure thereto and exhausting it therefrom, said controlling element provided exteriorly thereof with a lengthwise extending equalizing fin.

5. A salvaging unit of the submergible type comprising a controllable element adapted to receive a weighting means therefor, a plurality of fluid pressure receiving elevating elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling and elevating elements normally arranged in spaced parallel relation, said controlling element gradually increasing in diameter from its center towards each end and each of said elevating elements gradually decreasing in diameter from its center towards each end.

6. A salvaging unit of the submergible type comprising a controllable element adapted to receive a weighting means therefor, a plurality of fluid pressure receiving elevating elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling and elevating elements having means for supplying thereto and exhausting therefrom a weighted means therefor and for supplying fluid pressure thereto and exhausting it therefrom, said controlling element provided exteriorly thereof with a lengthwise extending equalizing fin, said controlling and elevating elements normally arranged in spaced parallel relation, said controlling element gradually increasing in diameter from its center towards each end and each of said elevating elements gradually decreasing in diameter from its center towards each end.

7. A salvaging unit of the submergible type comprising a controllable element adapted to receive a weighting means therefor, a plurality of fluid pressure receiving elevating elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling element provided exteriorly thereof with a lengthwise extending equalizing fin.

8. A salvaging unit of the submergible type comprising a controllable element adapted to receive a weighting means therefor, a plurality of fluid pressure receiving elevating elements connected with said controlling element and possessing a buoyant characteristic for moving upwardly relative to said controlling element when relieved of their weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling element provided exteriorly thereof with a lengthwise extending equalizing fin, said controlling and elevating elements normally arranged in spaced parallel relation, said controlling element gradually increasing in diameter from its center towards each end and each of said elevating elements gradually decreasing in diameter from its center towards each end.

9. A salvaging unit of the submergible type comprising a controllable element having means for supplying thereto and exhausting therefrom a weighting means therefor and fluid pressure, a bar disposed longitudinally and eccentrically of said element and projecting from each end thereof, oppositely extending grabbing elements pivotally mounted intermediate their ends on each end of said bar, means for connecting the ends of the bar to the ends of said controlling element,

12.

12.

130

a pair of elevating elements opposing said controlling element and each provided with means for supplying thereto and exhausting therefrom a weighting means therefor and fluid pressure, and a bar disposed axially of each elevating element, projecting from the ends thereof and having its ends connected with a pair of grabbing elements.

10. A salvaging unit of the submersible type comprising a controlling element having means for supplying thereto and exhausting therefrom a weighting means therefor and fluid pressure, a bar disposed longitudinally and eccentrically of said element and projecting from each end thereof, oppositely extending grabbing elements pivotally mounted intermediate their ends on each end of said bar, means for connecting the ends of the bar to the ends of said controlling element, a pair of elevating elements opposing said controlling element and each provided with means for supplying thereto and exhausting therefrom a weighting means therefor and fluid pressure, and a bar disposed axially of each elevating element, projecting from the ends thereof and having its ends connected with a pair of grabbing elements, said grabbing elements being hollow and each provided with a water intake and valve controlled air discharge means.

11. A salvaging unit of the submersible type comprising oppositely disposed grabbing elements, a weighted controlling element having said grabbing elements, intermediate their ends pivotally connected therewith, fluid pressure receiving means possessing a buoyant characteristic for moving relative to said controlling element when relieved of their weight by fluid pressure and connected with said grabbing elements for shifting them on their pivots to active position with respect to the object to be salvaged, and means carried by said controlling element for stabilizing the unit when submerging it and for retarding the upward movement of the controlling element on the upward movement of said means.

12. A salvaging unit of the submersible type comprising a submersible, weighted controlling element tending to retain the unit submerged, normally inactive, oppositely disposed grabbing elements for lifting the object to be salvaged and pivotally supported from said controlling element, and means movable upwardly relative to said controlling element, connected to said grabbing elements for shifting them to active position with respect to the object to be salvaged and for elevating the unit after the grabbing elements have been shifted to active position, said grabbing elements provided with means for the intake of water thereto to increase the weight thereof, and said elevating means and controlling element having means for sup-

plying thereto and exhausting therefrom a weighting means and fluid pressure.

13. A salvaging unit of the submersible type comprising normally inactive grabbing elements for lifting the object to be salvaged, pneumatically operated means for shifting said elements to lifting position with respect to the object to be salvaged and for elevating the unit after the grabbing elements have been shifted to lifting position, and weighted means for retarding the elevation of the unit and having said grabbing elements pivotally supported therefrom, said grabbing elements further connected with said pneumatically operated means.

14. A salvaging unit of the submersible type comprising a weighted controlling element, a pair of normally weighted elevating elements arranged in juxtaposition relative to said controlling element, means for making said elevating elements buoyant to provide for the upward movement thereof relative to and against retardation by the controlling element to raise the unit, and grabbing elements connected with the controlling element and shifted by said elevating elements on the upward movement of the latter to lifting position with respect to the object to be salvaged whereby on the upward movement of the unit the object will be carried therewith.

15. A salvaging unit of the submersible type comprising a controllable element adapted to receive a weighting means therefor, a plurality of fluid pressure and weight receiving elevating elements connected with said controlling element and possessing a buoyant characteristic for moving upwardly relative to said controlling element when relieved of its weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling element provided exteriorly thereof with a lengthwise extending equalizing fin.

16. A salvaging unit of the submersible type comprising a controllable element adapted to receive a weighting means therefor, a plurality of fluid pressure and water receiving elevating elements connected with said controlling element and possessing a buoyant characteristic for moving upwardly relative to said controlling element when relieved of its weight by fluid pressure, and grabbing elements pivoted intermediate their ends with said controlling element, connected at one end with said elevating elements and shiftable on their pivots to active position with respect to the object to be salvaged on the upward movement of said elevating elements, said controlling and elevating ele-

ments having means for supplying thereto and exhausting therefrom a weighted means therefor, and for supplying fluid pressure thereto and exhausting it therefrom, said controlling element provided exteriorly thereof with a lengthwise extending equalizing fin.

In testimony whereof, I affix my signature hereto.
